UNITED STATES PATENT OFFICE.

WALTER F. KOKEN, OF WEBSTER GROVES, MISSOURI.

DESIGN FOR A BARBER'S SIGN.

Application filed May 29, 1924. Serial No. 9,742. Term of patent 14 years.

To all whom it may concern:

Be it known that I, WALTER F. KOKEN, a citizen of the United States, residing at Webster Groves, St. Louis County, Missouri, have invented a certain new, original, and ornamental Design for a Barber's Sign, of which the following is a specification, reference being had to the accompanying drawing, forming part thereof.

The drawing illustrates the sign in front elevation.

I claim:

The ornamental design for a barber's sign, as shown.

WALTER F. KOKEN.
